(57) **CLAIM**

We claim the ornamental design for a medicine cabinet, as shown and described.

DESCRIPTION

FIG. 1 is a perspective view of a medicine cabinet showing our new design;

FIG. 2 is a front view thereof;

FIG. 3 is a cross-sectional view taken along line 3-3 in FIG. 2;

FIG. 4 is a cross-sectional view taken along line 4-4 in FIG. 2;

FIG. 5 is a cross-sectional view taken along line 5-5 in FIG. 2;

FIG. 6 is an enlarged detail view of the claimed design, shown in an alternate perspective;

FIG. 7 is an enlarged detail view of the cross-sectional view shown in FIG. 3;

FIG. 8 is an enlarged detail view of a portion of the front view shown in FIG. 2;

FIG. 9 is a cross-sectional view taken along line 9-9 in FIG. 7;

FIG. 10 is an enlarged detail view of a portion of FIG. 4; and, FIG. 11 is a cross-sectional view taken along 11-11 in FIG. 7.

The broken lines illustrating portions of the medicine cabinet form no part of the claimed design. The encircling broken lines in FIGS. 6-11 depict the unclaimed boundary of the enlarged detail views.
